George Payne, Bedford Hills, N.Y., and Joseph M. Finlay, Fairfield, Ohio, assignors to Mosler Safe Company, Hamilton, Ohio, a corporation of New York

Filed June 14, 1967, Ser. No. 7,472

Term of patent 14 years

(Cl. D69—1)

Fig. 1

FIGURE 1 is a front perspective of a day gate for a vault showing our new design;

FIGURE 2 is a front elevational view thereof;

FIGURE 3 is a rear elevational view thereof;

FIGURE 4 is a cross-sectional view taken on line 4-4 of FIGURE 2;

FIGURE 5 is a side elevational view taken from the left of FIGURE 2;

FIGURE 6 is a side elevational view taken from the right of FIGURE 2;

FIGURE 7 is a top plan view thereof; and

FIGURE 8 is a bottom plan view thereof.

The broken line representation of a vault entrance in FIGURE 1 is for purposes of illustration only, it being understood that portions of FIGURES 5 and 6 are broken away for convenience of illustration.

We claim:

The ornamental design for a day gate for a vault, substantially as shown and described.
